UNITED STATES PATENT OFFICE.

JAMES MILTON SANDERS AND WILLIAM A. STAMATS, OF MORRISVILLE,
OHIO; SAID SANDERS ASSIGNOR TO SAID STAMATS.

DISH FOR TABLE USE.

SPECIFICATION forming part of Letters Patent No. 371,631, dated October 18, 1887.

Application filed February 2, 1887. Serial No. 226,277. (No model.)

To all whom it may concern:

Be it known that we, JAMES MILTON SANDERS and WILLIAM A. STAMATS, both of Morrisville, in the county of Clinton and State of Ohio, have invented a new and useful Improvement in Dishes for Table Use, of which the following is a full, clear, and exact description.

This invention consists in a dish of novel construction for table use, provided with various receptacles or projections, substantially as hereinafter described, and pointed out in the claim, whereby increased conveniences are afforded and one and the same dish answers several uses.

Reference is to be had to the accompanying drawings, forming a part of this specification, in which similar letters of reference indicate corresponding parts in all the figures.

Figure 1 represents a top or plan view of a dish embodying our invention. Fig. 2 is a transverse section of the same upon the line *x x* in Fig. 1, and Fig. 3 a transverse section at right angles to Fig. 2 upon the line *y y* in Fig. 1.

The dish, which may be made of earthenware, porcelain, or any other suitable material, is generally of flat contour, with a bowl, *A*, of any desired size and depth for holding the viands to be served or placed upon the dish, of which letter *b* indicates the front.

Upon opposite sides of the bowl portion *A* are wings or flanges *B B*, of concave or recessed construction on their upper surfaces, and arranged to run in the direction of from front to back of the dish. These recessed flanges or portions serve to hold, respectively,

the one the fork and the other the knife of the person using the dish, when said articles are not being utilized.

At the back of the dish is another flange, wing, or receptacle, *C*, for holding the napkin, bread, refuse of the meal, or other articles or substances, as may be found convenient. This flange or wing has a raised rim, *e*, which serves to prevent the article or materials placed upon it from slipping off.

A plate or dish thus constructed will be found exceedingly convenient both for family and other use, and will serve to preserve neatness at the table and to prevent soiling of the table-cloth.

We are aware that a separate and detachable fork-and-knife holding shelf or attachment has before been applied to the edge of a dish; also, that a dish or plate consisting of three or more food-receptacles, a holder for cup or glass, and a handle has before been used; neither of such therefore do we claim.

Having thus described our invention, what we claim as new, and desire to secure by Letters Patent, is—

The dish constructed with a bowl portion, *A*, side wings or flanges, *B B*, of concave construction transversely on their upper surfaces throughout their length, and a back wing, flange, or receptacle, *C*, essentially as shown and described, and for the purposes herein set forth.

JAMES MILTON SANDERS.
WILLIAM A. STAMATS.
